UNITED STATES PATENT OFFICE.

HERMANN REICHE, OF MILLSTONE, NEW JERSEY.

FLYING MACHINE.

1,137,533.

Specification of Letters Patent Patented Apr. 27, 1915.

Application filed November 10, 1909. Serial No. 527,325.

To all whom it may concern:

Be it known that I, HERMANN REICHE, a citizen of the United States, residing at Millstone, Somerset county, State of New Jersey, 5 have invented new and useful Improvements in Flying-Machines, of which the following is a specification.

This invention relates to flying machines, particularly of that type known as aeroplanes, and its object is to provide means of creating a variable current of air along the under surfaces of moving, adjustable planes and converting its horizontal force into lifting energy. Its further objects are 10 to provide means for raising a flying machine at any angle. Means for propelling it in all directions. Means for holding it in a fixed position while suspended. Means for propelling and guiding it along the 15 ground. Means for supporting, propelling and guiding it on water. Means for operating its engine from any convenient part of the machine. Means for cutting out the 20 resistance of the engine. Means for reducing the extent of area of supporting planes and the total weight of aeroplanes. Means for 25 attaching the planes in such a way that they may be expanded or folded automatically or mechanically, and also caused to assume various 30 inclinations, for the purpose of acting as parachutes, or as aids in maintaining the machine afloat while in motion.

The means ordinarily employed to obtain 35 lifting force in motor-driven aeroplanes, is to project fixed planes through the air at high speeds. A modification of the above, the so-called gliding flight, provides a plane launched upon the air and permitted to glide to earth, by gravity, with a forward movement.

Another means of obtaining "lift" is the use of oscillating planes resembling in shape and movement the beating wings of birds, etc.

By combining the main principles of the above-mentioned means, I overcome draw backs and faults inherent in each type individually and obtain a flying machine having advantages and novel features, not otherwise found.

In the specific form herein considered, the machine is provided with a number of adjustable blowers or propellers rotating in opposite directions to balance their lateral

torque and designed to create a current of air along the under surfaces of vertically or obliquely reciprocating planes. The velocity of the current being greater than the vertical speed of the planes, and these being more or less tilted upwardly at their forward edge, there will be a constant upward pressure against their lower sides.

Other matters remaining the same, I have found that the upward pressure or lift increases equally with the inclination of the planes, while the retarding pressure or "drift" increases approximately as the square of their inclination, thus a degree of inclination may be reached when the drift balances or overcomes the forward impulsion of the machine, and therefore, as all parts of the machine are adjustable, it may be driven at any speed and angle from horizontal to vertical, forward and backward, or held in a fixed position while suspended.

In the accompanying drawings, Fig. 1 is a side elevation of my improved flying machine, with some of the parts omitted; Fig. 2 a front elevation thereof, with some of the parts omitted and showing the lateral planes distanced from the upper planes; Fig. 3 a plan, partly broken away, of the flying machine; Fig. 4 a plan, partly in section, of the motor and adjoining parts; Fig. 5 a cross section through the right hand end of Fig. 4; Fig. 6 a detail section through part of the means for raising and twisting the lateral planes; Fig. 7 a similar section through part of the means for setting the lifting plane guides; and Fig. 8 a detail of Fig. 1, and Fig. 9 a detail of the differential gear.

The framework A of the air ship or flying machine consists essentially of a number of vertical posts, the ends are firmly connected by longitudinal beams 11, 13, 15 and transverse beams 14. Within frame A are rotatably mounted a suitable number of propellers, the drawing showing two propellers B and C. Of these front propeller B, is fast on a longitudinal shaft 14 supported in bearings 16, while rear propeller C, is loose on such shaft. The latter receives rotary movement from a suitable motor, a four-cylinder gasoline motor 17 being shown. The valves 18 of the several motor-cylinders are controlled by arms 19, fulcrumed to a ship-ping bar 20 having bar 21.

Upon the protruding ends of the motor shaft 22 are slidably mounted friction disks 23, 24 held against rotation upon said shaft by keys 25. Opposite the outer face of disk 23, a friction wheel 26 is slidably fitted on a vertical shaft 27, which is mounted in bearings 28, a feather 29 of shaft 27 preventing an independent rotation of wheel 26. The latter may be vertically adjusted upon shaft 27, for which purpose the hub 30 of the wheel is provided with a circumferential groove into which a ring 31 is loosely fitted. To the latter is fulcrumed the forked end of a link 32, pivoted to the arm 33 of an elbow 15 lever, the other arm 34 of which constitutes a handle. By tilting handle 34 forward or backward, friction wheel 26 may be shifted downward or upward upon shaft 27, as will be readily understood.

Friction disk 23 is adapted to be forced against wheel 26, so as to take the latter along during the rotation of shaft 22. For this purpose the case of motor 17 is provided with a threaded sleeve 35, which also 25 constitutes a bearing for shaft 22. Sleeve 35 is embraced by an internally threaded ring 36 provided with a laterally extending arm 37. The side of ring 36 which faces hub 38 of disk 23, is provided with an annular 30 recess 39 which constitutes the race for anti-friction balls 40. The outer end of arm 37 is, by a universal joint 41, connected to the forward end of a two-arm lever 42, the rear end of which carries a treadle 43. Lever 42 35 is fulcrumed upon a transverse rod 44 secured to motor 17 by bracket 45. It will be seen that by depressing treadle 43, ring 36 will be turned on sleeve 35 and will be screwed against hub 38 to force disk 23 into 40 operative engagement with wheel 26, the balls 40 preventing friction between ring and hub. Upon the release of treadle 43, disk 23 will be relieved from pressure, so that wheel 26 will no longer be taken along 45 by said disk.

To the upper end of a shaft 27 is secured a beveled gear wheel 46 meshing into a similar wheel 47 fast on shaft 15. To the latter is further keyed a beveled gear wheel 48 50 meshing into a gear wheel 49 of smaller diameter. Wheel 49 is fast on a vertical arbor 50 turning in a bearing 51 and carrying a larger gear wheel 52. The latter meshes into a similar wheel 53 loosely 55 bracing shaft 15 and secured to the hub 54 of propeller C. It will be seen that wheels 48, 49, 52, 53 jointly constitute a reversing gear and also an increasing speed gear, owing to the difference in the diameters of 60 wheels 48 and 49. Thus, if friction wheel 26 is so set as to impart the desired rotary movement to propeller B, propeller C, will simultaneously be rotated in the opposite direction and at an increased speed for a purpose 65 hereinafter explained. In order to

cause both propellers to coöperate in advancing the ship, the position of the vanes of propeller C, are reversed relatively to those of propeller B, as illustrated in Figs. 1 and 3.

At a distance back of propeller B, there are located a series of superposed oblong planes 55 which are adapted to receive an alternating upward and downward movement in manner hereinafter described. Planes 55 are curved in cross section and have a lower concave surface. The vertical energy created by the downward movement of the planes is utilized for raising the ship and sustaining it at the desired elevation. The lifting power of the curved planes is considerably increased by the action of the propeller B, which is arranged in front thereof and thus throws the air against the planes, which effect may be considerably augmented by tilting the planes backward, as hereinafter more fully described.

Similar to planes 55, there are arranged back of propeller C, a series of vertically reciprocal curved planes 56, against which the air is thrown by said propeller. But as there is already generated, by the front propeller B, an air current within the framework of the air ship, which would greatly diminish the effect of propeller C, were the latter to turn with the same speed as propeller B, the above-mentioned reversing and increasing speed gear 48, 49, 52, 53 is provided, which enables the rear propeller C, to obtain a firm grip on the air current created by the front propeller B. As propeller C, turns in a direction opposite to that of propeller B, the vanes of the former are set reversed to those of the latter, as above described.

For properly supporting and operating planes 55, 56, the following construction has been devised: In the lower longitudinal beams 11 of the air ship frame are hung a pair of parallel transverse shafts 57, 58 which are operatively connected to each other by an endless chain 59 engaging corresponding chain wheels of said shafts. On shaft 57 is slidably mounted a friction wheel 60, the independent rotation of which is prevented by a feather 61. Wheel 60 is adapted to be engaged by the friction disk 24, hereinabove referred to. In order to effect an operative engagement between parts 24 and 60, a fixed threaded sleeve 62 embraces the right hand end of shaft 22, (Figs. 4 and 5). Sleeve 62 is engaged by an internally threaded ring 63 having a laterally extending arm 64. That side of ring 63 which faces friction disk 24 is provided with an annular groove that constitutes the race for anti-friction balls 65. The latter are adapted to engage a flange 66 formed on hub 67 of disk 24. Arm 64 is, by a universal joint 68, connected to a lever 69 fulcrumed to rod 130

44 and having treadle 70. It will be seen that by depressing the latter, ring 63 will be rotated to bring balls 65 into contact with the flange 66 of disk 24, and to thereby shift the latter into operative engagement with friction wheel 60.

In order to regulate the speed of shafts 57, 58, wheel 60 may be shifted transversely into any desired position relative to disk 24, for which purpose a fixed cross bar 71 is provided between beams 11. Upon the latter is movably mounted a slide 72 having an upwardly extending handle 73 and furnished with suitable locking means. From 15 slide 72 extends forwardly an arm 74 having a forked end 75 that engages a groove 76 formed in the hub of wheel 60. By transversely shifting slide 72, wheel 60 may be set at any desired distance from the center 20 of disk 24, so that the speed of shafts 57 and 58 may be regulated.

Upon shaft 57 are loosely mounted a pair of tiltable guide rails 77 slotted as at 78 for the accommodation of the outer ends of 25 transverse rods 79, 80. These rods are fitted between a pair of parallel bars 81, and carry the lower and upper planes 55, respectively, which are securely attached to said rods. The central plane 55 is divided vertically to 30 accommodate between its sections the longitudinal propeller shaft 15. Flanking said shaft, there are arranged a pair of parallel upright stays 82 which are interposed between lower and upper rods 79, 80. Bars 35 81 and 82 are connected by a pair of axially aligned rods 83 to which the sections of the central plane 55 are secured. To the outer ends of rod 79 are wristed the upper ends of pitmans 84, the lower ends of which are fulcrumed to 40 cranks 85 secured to shaft 57. In like manner, there turn loosely on shaft 58, a pair of guide rails 86 slotted as at 87 for the accommodation of the rods 79, 80, of the rear planes 56, said rear planes and their 45 supporting frame 81, 82 being duplicates of the front planes and frame. The outer ends of rod 79 carrying lower plane 56 are engaged by the upper ends of pitmans 88, the lower ends of which are fulcrumed to 50 cranks 89 mounted on shaft 58.

It will be seen that when the rotating disk 55 is forced against friction wheel 60, shafts 57, 58 are simultaneously rotated with a uniform speed, so that a vertical reciprocative 55 movement is imparted to planes 55, 56 by cranks 85, 89 and pitmans 84, 88. Cranks 85, 89 are preferably so set on their shafts, that while planes 55 ascend, planes 56 descend, and vice versa.

60 In order to adapt planes 55 and 56 to currents of various strength and to fully utilize the air currents generated by the propellers, guide rails 77 and 86, together with their plane-supporting frames and the planes 65 themselves, may be tilted either forward or

backward. This tilting may take place either simultaneously or independently for both sets of planes.

To longitudinal beams 12 are secured a pair of U-shaped frames or bearings 90 70 within which is journaled a transverse shaft 91 which passes also through beams 12. Shaft 91 carries a hand wheel 92 and is held against accidental axial displacement by a pair of springs 93 secured to frames 90, said 75 springs also serving to return the shaft to its normal position after it has been axially shifted for a purpose hereinafter described. Within each frame 90 there are loosely mounted upon shaft 91, a pair of gear 80 wheels 94, 95, which mesh, respectively, into the correspondingly toothed sections of longitudinally movable shipping rods 96, 97. These rods are supported upon rollers 98, 99 loosely turning on axle 100 which traverses frame 90. Rods 96 are, by links 101, operatively connected to guides 77, while rods 97 are, by links 102, connected to guides 86. For operating the shipping rods, gear wheels 94, 95 are provided with inner toothed recesses 103, 104 which are adapted to be engaged, either jointly or severally, by pinions 105 fast on shaft 91.

Normally, springs 93 co-act to maintain shaft 91 in its central position, so that pinions 105 are centered between gear wheels 94, 95 and engage the toothed recesses of both of said wheels. By turning hand wheel 92 in one or the other direction, guide rails 77 and 86 are simultaneously swung in the same direction, so as to tilt planes 55, 56 either backward or forward. If it is desired to set planes 56 only, while planes 55 are to retain their position, hand wheel 92 is slightly pushed toward the right, so that pinions 105 will engage gear wheels 95 only, (Fig. 7), and will thus influence guides 86 alone. In like manner, if it is desired to actuate planes 55 only, hand wheel 92 is pushed toward the left, so that pinions 105, 110 will engage wheels 94, as will be readily understood.

The upper longitudinal beams 13 of frame A, are connected by a number of parallel transverse spindles 196, three of such spindles being shown. Upon each spindle is rigidly mounted a pair of arms 107, to which are fulcrumed a pair of longitudinal rods 108. The latter are connected by a series of concaved aeroplanes 109 that assist planes 55 and 56 in maintaining the air ship at the desired elevation.

Planes 109 are operatively connected in the manner hereinafter described, to a series of lateral planes or wings D, four of such planes being shown at each side of the ship. Each wing comprises essentially a central rib 110 and a pair of outer ribs 111 which are connected by a suitable number of transverse ribs 112, the frame thus formed being 120

- covered with silk, canvas or other suitable material. Central rib 110 is hung on a pin-tle 113 turning in bearings 114 which extend laterally from the outer face of a pinion 115, 5 which is rotatably supported by longitudinal beam 13. At their extreme outer ends, the wings arranged at one side of the ship are connected by a common binder 112.
- To the outer side of central rib 110 of 10 each wing D, is secured one end of a guy 116, the other end of which is connected to one of the rods 108. At their inner or lower sides, ribs 110 are connected by guys 117 to barrels 118 hung on longitudinal shafts 119.
- 15 The latter are rotatably mounted in bearings 120 extending from beams 12. It will be seen that by raising rods 108 and planes 109, the wings D, will be swung upward by guys 116, thereby unwinding guys 117 from barrels 118. For returning the wings to their collapsed state, barrels 118 are rotated to wind up guys 117, which action will also lower planes 109.
- For manipulating planes 109 and wings 20 D, a transverse shaft 121 is provided which turns in bearings 122, 123 secured by brackets 124, 125 to the central posts 10. Upon the outer ends of shaft 121 are fitted bevel gear wheels 126 which engage similar wheels 25 127 mounted on shafts 119. Intermediate wheels 126 and posts 10 there is secured to shaft 121 a pair of sprocket wheels 128 which are, by chains 129, connected to sprocket wheels 130 keyed to the outer ends 30 of central spindle 106 hereinabove referred to. Wheel 130 is near its circumference secured to arms 107 as at 131. For actuating shaft 121 a hand wheel 132 is slidably mounted thereon, a groove and feather connection 133 preventing independent rotation 35 of the hand wheel. The hub 134 of wheel 132 is serrated as at 135 to form a first clutch-member adapted to engage a correspondingly serrated cup or second clutch- 40 member 136 formed at the free end of a sleeve 137 which embraces shaft 121 and forms part of bearing 123. Intermediate bearing 122 and hand wheel 132, a spring 138 is interposed, which tends to close the 45 clutch and thus prevents an accidental rotation of shaft 121.
- If it is desired to raise planes D, hand wheel 132 is slightly moved toward the left, (Fig. 6), to open the clutch, and then the 50 hand wheel is turned. The rotation thus imparted to shaft 121 effects, by sprocket wheels 128 and chains 129, a partial rotation of sprocket wheels 130, and as arms 107 are attached to the latter, rods 108, together with planes 109, will be raised. The 55 ascent of rods 108 is, by guys 116, transmitted to wings D, which will thus swing upward on their pivots 113. By this upward movement of wings D, the guys 117 60 are unwound from barrels 118, their shafts 65 119 being so intergeared with shaft 121, by wheels 127, 126, as to permit a corresponding rotation of the barrels. For lowering wings D, hand wheel 132 is turned in the opposite direction, whereby guys 117 will be wound upon barrels 118, the latter receiving rotary movement through gear wheels 126, 127. Simultaneously rods 108 and planes 109 are lowered, owing to the connection between central arms 107 and sprocket 70 wheels 130, which receive rotary motion from shaft 121 through sprocket wheels 128 and chains 129, as will be readily understood.
- The ribs 110 and 111 of the several wings 80 D, are made of elastic material, so that the inner ends of the wings may be twisted, while their outer ends, which are connected by binder 112, remain in longitudinal alignment. In this way the wings may be considerably distorted by imparting to them a spiral twist, for which purpose the wings are hinged to the rotatable pinions 115, hereinabove referred to. The means for rotating pinions 115 are such as to permit an adjustment of the pinions located at one side of the air ship independent from those located at the other side thereof, which separate adjustment may be found necessary.
- For operating pinions 115, the transverse 85 shaft 121 is embraced, near its ends, by a pair of sleeves 139, which are rotatably mounted in central posts 10 and thus assist bearings 122, 123 in supporting shaft 121. Upon each sleeve is slidably mounted a hand wheel 140, rotation of said wheel upon sleeve 139 being prevented by a suitable groove and feather connection 141. The enlarged end of the wheel-hub 142 is serrated to form a first clutch-member adapted to engage the 90 correspondingly serrated edge of a second clutch-member or cup 143 secured to central posts 10. The clutches are normally closed by springs 144 interposed between wheels 140 and bearings 122, 123, respectively. Integral with the outer ends of sleeves 139, are sprocket wheels 145, which, by chains 146, are connected to sprocket 95 wheels 147. Each sprocket wheel 147 is secured to the outer face of a pinion 148 meshing into the toothed lower edge 149 of a shipping rod 150 which is slidably secured by guide rollers 151 to longitudinal beams 13. At its upper edge rod 150 is provided with a series of toothed sections 152 that engage the pinions 115 hereinabove referred to.
- It will be seen that after drawing hand 100 wheels 140 out of engagement with cups 143, said wheels may be freely rotated, which movement is transmitted to pinions 115 by 105 sprocket wheels 145, chains 146, sprocket wheels 147, pinions 148, and shipping rods 150. By properly setting pinions 115, wings D, may be twisted to any extent desired.
- For laterally steering the air ship, a ver- 110 115 120 125 130

tical rudder 153 is secured to an upright spindle 154. The latter is journaled in a pair of cross bars 155 forming part of the frame-work of the air ship. Rudder 153 may be set by hand wheel 156 carried by a vertical arbor 157 which is rotatably mounted in a suitable standard 158. To the lower end of arbor 157 is secured a sprocket wheel 159 which is, by chain 160, connected to a sprocket wheel 161 rigidly mounted upon the rudder spindle 154. By properly turning hand wheel 156, the rudder may be set at any inclination desired, as will be readily understood.

15 To permit the air ship to be steered when its headway is insufficient for insuring a proper action of the rudder, a steering propeller 162 is provided which is accommodated within a corresponding recess 163 formed in the rudder. Propeller 162 is mounted upon an arbor 164 rotatably supported by the rudder-frame and connected by a universal joint 165 to a shaft 166. The latter turns in a fixed bearing 167 and carries at its free end a bevel wheel 168 meshing into a similar wheel 169 fast on shaft 166. The latter receives continuous rotary motion during the movement of shafts 17 and 58, so that a proper and effective steering action is obtained, even when the ship travels at a lower speed.

The air ship is preferably provided with front runners or wheels 170 and with rear wheels 171. Wheels 170 are fast on the outer ends of a transverse axle 170^a, which is rotatably mounted in a tubular sleeve 172 secured by brackets 173 to the lower longitudinal beams 11. At its outer ends sleeve 172 terminates in a pair of semi-circular hoods 174 designed to cover the upper halves of wheels 170. At its center, sleeve 172 is provided with a raised 175 mounting a balanced differential gear 176 carried by axle 170^a, said gear being only diagrammatically shown in Fig. 2. Gear wheel 176 engages a bevelled gear wheel 177 fast on the lower end of vertical shaft 27. Thus, upon the rotation of the latter, wheels 170 are turned by gear 177, 176 to advance the air ship along the ground, while its speed may be regulated by vertically adjusting friction wheel 26. During this travel of the air ship its course is controlled by the rear steering wheels 171 which are carried by sleeves 178 pivoted to the frame at 179. The tops of wheels 171 are embraced by sleeves 180 having arms 181 to which is pivoted at 182 a connecting rod 183. To pivots 182 are secured the ends of a chain 184 engaging a sprocket wheel 185 fast on the lower end of spindle 154. It will be seen that by turning hand wheel 156, rear wheels 171 are deflected in unison with the adjustment of the rudder and rudder-propeller, so that the course of the air ship, when travel-

ing over the ground, may be readily controlled.

Below sleeve 172 and axles 170^a, 178 there is suspended from the bottom of the air ship by brackets 186 a float 187 of sufficient buoyancy to sustain the ship when the latter should enter the water. For propelling the ship upon the water, the spokes of wheels 170 are provided with paddles 188, as shown. To the forward end of float 187 is hinged at 189 a horizontal rudder 190 designed to control the ascent and descent of the ship. Rudder 190 is, by links 191, connected to a pair of levers 192 fast on a transverse shaft 193 journaled in beams 11. One of these levers 192 has an elbow 194 which is, by rod 195, connected to a hand lever 196 fulcrumed at 197 and provided with a suitable locking device 198. By turning lever 196 forward or backward, rudder 190 will be lowered or raised, as will be readily understood.

If it is desired to fly the air ship, motor 17 is started, for which purpose any desired means may be employed. The drawing shows the flanged hub 67 of disk 24 to be 90 embraced by a loose sleeve 199 having a circumferential helical groove 200. The latter is engaged by a stationary pin 201 connected by a bracket 202 to the case of motor 17. Sleeve 199 has a circular groove 203 engaged by a rope 204, one end of which is secured to a spring 205, hung to beam 11. The other end of rope 204 is passed around a pulley 206 and carries a handle 207. Sleeve 199 is provided at its outer face with clutch teeth 208 adapted to engage similar teeth 209 on disk 24. By manipulating handle 207, sleeve 199 is turned and advanced toward disk 24, owing to the engagement of pin 201 with groove 200, so that disk 24 will 105 be taken along by teeth 208, 209.

It will be seen that the air ship is provided with readily operable means for regulating the number of rotations of the propellers, so that the speed of the ship may be varied at 110 pleasure. In like manner, the velocity of the vertical movement of the lifting planes may be easily controlled, so that a greater or smaller rising tendency may be imparted to the ship. Although the current-creating 115 mechanisms B and C, herein designated as propellers, have a propelling effect on the machine by reason of their reactive thrust, their main function is to produce a current of air along the undersides of the planes 55 120 and 56. The progress of the machine, while suspended, is mainly caused by converting its gravity into horizontal energy, regulated by the adjustment of the various planes. The propellers may be placed in front of, or 125 behind the lifting planes. In fact, by reversing the rotation of propellers B and C, and the inclination of the planes 55 and 56, the ends of the machine are reversed relative to its progress.

I do not wish to be restricted to this form of propellers, as any mechanism designed to create a current may be employed. Nor do I wish to be restricted to the use of reciprocating lifting planes, as other planes having a continuous movement, with their course and inclinations mechanically governed, may be employed.

I claim:

- 10 1. A flying machine provided with a front propeller, a series of lifting planes located back thereof, a rear propeller rotating with a higher speed and in a direction opposite to that of the front propeller, a series of lifting planes located back of the rear propeller, and means for vertically reciprocating both series of planes.
- 15 2. In a flying machine, the combination of an air propeller and a series of co-operating reciprocal lifting planes located back thereof and inclined relatively to the current produced by said propeller, and means for varying the course of said planes.
- 20 3. In a flying machine, the combination of an air propeller, a guide located back thereof, reciprocal lifting planes engaging said guide and inclined relatively to the air current produced by the propeller, and means for varying the inclination of the guide.
- 25 4. A flying machine comprising a frame, a propeller, a guide fulcrumed to the frame, reciprocal lifting planes engaging said guide and inclined relatively to the air current produced by the propeller, and means for tilting the guide.
- 30 5. A flying machine provided with a frame, a front propeller, a first guide fulcrumed to the frame back of the front propeller, a rear propeller, a second guide fulcrumed to the frame back of the rear propeller, reciprocal lifting planes engaging the guides, and means for tilting the first and second guides, either jointly or separately.
- 35 6. A flying machine provided with a frame, a transverse shaft rotatably mounted therein, cranks on said shaft, slotted guides loosely embracing the shaft, means for adjusting said guides, connected upper and lower rods engaging the guide-slots, lifting planes secured to the rods, and links connecting the cranks with one of said rods.
- 40 7. A flying machine provided with a frame, a transverse shaft rotatably mounted therein, cranks on said shaft, slotted guides loosely embracing the shaft, means for adjusting said guides, an upper rod and a lower rod engaging the guide-slots, bars connecting said rods, lifting planes secured to the rods, and links connecting the cranks with the lower rods.
- 45 8. A flying machine provided with a frame, a transverse shaft rotatably mounted therein, cranks on said shaft, slotted guides loosely embracing the shaft, means for adjusting said guides, means for

adjusting said guides, an upper rod and a lower rod engaging the guide-slots, bars connecting the rods near their outer ends, a pair of parallel stays intermediate said bars, central rods connecting the bars and stays, lifting planes secured to all of said rods, and links connecting the cranks with the lower rods.

9. A flying machine provided with a frame, an axially displaceable transverse shaft hung therein, a pinion fast on said shaft, a pair of gear wheels loosely embracing the shaft and having toothed recesses which are adapted to be engaged by the pinion, toothed shipping rods engaging the gear wheels, guides fulcrumed to the frame and operatively connected to the rods, and reciprocative lifting planes engaging the guides.

10. A flying machine provided with a frame, an axially displaceable transverse shaft hung therein, a pair of springs adapted to center said shaft, a pinion fast on the shaft, a pair of gear wheels loosely embracing the shaft and having toothed recesses which are adapted to be engaged by the pinion, toothed shipping rods engaging the gear wheels, pivoted guides linked to the rods, and reciprocative lifting planes engaging the guides.

11. A flying machine provided with a frame, U-shaped bearings secured thereto, an axially displaceable transverse shaft hung therein, a pair of springs secured to the bearings and adapted to center the shaft, a pinion fast on said shaft, a pair of gear wheels loosely embracing the shaft and having toothed recesses which are adapted to be engaged by the pinion, toothed shipping rods engaging the gear wheels, rollers turning in the bearings and supporting the shipping rods, pivoted guides linked to said rods, and reciprocative lifting planes engaging the guides.

12. A flying machine provided with a frame, a series of pinions rotatable thereon, lugs formed on the pinions, folding wings hinged to said lugs, means for raising and lowering said wings, and means operable by the pinions for helically distorting said wings to vary the angle of incidence of said wings.

13. A flying machine provided with a series of side wings, means for connecting the outer ends of said wings to each other, and means for twisting the inner ends of said wings.

14. A flying machine provided with a frame, a series of pinions rotatable thereon, wings hinged to the pinions, binders connecting the free ends of the wings, means for raising and lowering the wings, and means for turning the pinions.

15. A flying machine provided with a frame, a series of pinions rotatable thereon,

wings having ribs which are hinged to the pinions, binders connecting the free ends of the wings, means for raising and lowering the wings and means for turning the pinions.

16. A flying machine provided with a frame, a series of pinions rotatable thereon, a rack engaging said pinions, wings hinged to the pinions, a binder connecting the free ends of the wings, means for raising and lowering the wings, and means for shifting the rack.

17. A flying machine provided with a frame, lateral wings hinged thereto, arms fulcrumed to the frame, a longitudinal rod carried by the arms, guys connecting said rod with the wings, and means for tilting the arms.

18. A flying machine provided with a frame, lateral wings hinged thereto, arms fulcrumed to the frame, a longitudinal rod pivoted to the arms, first guys connecting said rod with the wings, barrels rotatably mounted on the frame, second guys connecting the barrels with the wings, and means for simultaneously tilting the arms and rotating the barrels.

19. A flying machine provided with a frame, pinions rotatable thereon, wings hinged to the pinions, arms fulcrumed to the frame, a longitudinal rod carried by the arms, first guys connecting said rod with the wings, barrels rotatably mounted on the frame, second guys connecting the barrels with the wings, means for simultaneously tilting the arms and rotating the barrels, and means for turning the pinions.

20. A flying machine provided with a frame, lateral wings hinged thereto, arms fulcrumed to the frame, longitudinal rods carried by the arms, an aeroplane supported by the rods, guys connecting said rods with the wings, and means for tilting the arms.

21. A flying machine provided with a frame, a series of wings hinged thereto, a transverse shaft hung in the frame, a sprocket wheel and a gear wheel fast on said shaft, means controlled by the sprocket wheel for raising the wings, and means controlled by the gear wheel for lowering said wings.

22. A flying machine provided with a frame, a series of wings hinged thereto, a transverse shaft hung in the frame, a hand wheel slideable on said shaft, means for locking said wheel against rotation, a sprocket wheel and a gear wheel fast on the shaft, means controlled by the sprocket wheel for raising the wings, and means controlled by the gear wheel for lowering said wings.

23. A flying machine provided with a frame, a series of pinions rotatable thereon, wings hinged to the pinions, a transverse shaft hung in the frame, a first sprocket

wheel and a gear wheel fast on said shaft, a sleeve loosely embracing the shaft, a second sprocket wheel fast on the sleeve, means controlled by the first sprocket wheel for raising the wings, means controlled by the gear wheel for lowering the wings, and means controlled by the second sprocket wheel for turning the pinions.

24. A flying machine provided with a frame, a series of wings hinged thereto, a longitudinal shaft rotatably mounted on said frame, barrels fast on said shaft, guys connecting said barrels with the wings, and means comprising a rotatable transverse shaft hung in said frame and intergeared with said longitudinal shaft for raising and lowering said wings upon the rotation of said transverse shaft, and a hand wheel for rotating said transverse shaft.

25. A flying machine provided with a frame, wings hinged thereto, brackets secured to the frame, a transverse shaft hung in said brackets, a tubular sleeve formed on one of said brackets and surrounding the shaft, a first clutch-member on the sleeve, a hand wheel slidably mounted on the shaft and having a second clutch-member, a spring engaging the hand wheel, and means for operatively connecting the shaft to the wings.

26. A flying machine provided with a frame, a series of pinions rotatable thereon, wings hinged to the pinions, a transverse shaft hung in the frame, a sleeve loosely embracing the shaft, means for locking said sleeve against rotation, a first sprocket wheel fast on the sleeve, a second sprocket wheel fulcrumed to the frame, a chain connecting both sprocket wheels, a toothed wheel secured to the second sprocket wheel, and a rack having lower teeth adapted to engage the toothed wheel, and upper teeth adapted to engage the pinions.

27. A flying machine provided with a frame, a series of pinions rotatable thereon, wings hinged to the pinions, brackets secured to the frame, a transverse shaft hung in said brackets, a sleeve loosely embracing the shaft, a hand wheel for rotating the sleeve and slideable on same, means for locking said wheel against rotation, and means for operatively connecting the sleeve to the pinions.

28. A flying machine provided with a frame, a series of pinions rotatable thereon, wings hinged to the pinions, brackets secured to the frame, a transverse shaft hung in said brackets, a sleeve loosely embracing the shaft, a spring-influenced hand-wheel for rotating said sleeve and slideable on the same and having a serrated hub, a fixed serrated cup adapted to be engaged by the hub, and means for operatively connecting the sleeve to the pinions.

29. In a flying machine having a frame

- and a motor thereon, lifting planes operated by said motor, means for varying the inclination and course of said planes, and a plurality of air propellers operated by said motor and adapted to lead a current of air against the under surfaces of said planes, the combination of a vertical rudder and a rudder propeller fulcrumed to the rear portion of the frame, and a horizontal rudder fulcrumed to the front portion of the frame. 10
30. In a flying machine having a frame and a motor thereon, lifting planes operated by said motor, means for varying the inclination and course of said planes, and a plurality of air propellers operated by said motor, and adapted to lead a current of air against the under surfaces of said planes, the combination of a horizontal rudder fulcrumed to the front portion of the frame, a 15 vertical rudder and a rudder propeller fulcrumed to the rear portion of the frame, and means for operating the rudder propeller. 20
31. A flying machine comprising a frame, a pair of propellers, curved lifting planes influenced thereby, means for guiding the planes, regulable means for rotating the propellers, regulable means for reciprocating the planes, means for varying the dip of the 25 guiding means, a vertical rudder and a rudder propeller fulcrumed to the rear portion of the frame, steering wheels pivoted to the frame, and means for operatively connecting the rudder with said wheels. 30
32. A flying machine comprising a frame, a pair of propellers, curved lifting planes influenced thereby, means for guiding the planes, regulable means for rotating the propellers, regulable means for reciprocating 35 the planes, means for varying the dip of the guiding means, a vertical rudder and a rudder propeller fulcrumed to the rear portion of the frame, a float depending from the frame, front traction wheels and rear steering wheels pivoted to the frame, paddles on the front wheels, means for operatively connecting the front wheels to the propeller-rotating means, and means for operatively connecting the rudder with the steering 40 wheels. 45
33. In a flying machine the combination of movable lifting planes, air propellers arranged to lead currents of air against the under surfaces of said planes, means for operating said propellers at variable speeds, means for reversing said propellers, means for imparting a forward and downward movement to said planes, means for changing the same to a backward and downward 50 movement, and means for varying the inclination of said planes in respect to the propeller currents. 55
34. In a flying machine, a frame, propellers mounted therein, levitating planes, means for moving said planes in a forward 60
- and downward direction with respect to said frame, a crankshaft forming an operative connection between said propellers and planes, power pistons rotatably attached to said crankshaft, cylinders embracing said pistons, means for generating power in said cylinders to drive said pistons, means comprising exhaust valves adapted to relieve the resistance to said pistons due to compression in said cylinders, and a mechanism adapted to simultaneously actuate said valves. 70
35. In a flying machine, a frame, a motor, means for creating a current of air, means for regulating said current, a plurality of planes inclined with respect to said current, means for varying the inclination of said planes, and means for moving said planes within said frame obliquely across said current. 80
36. In a flying machine the combination of a frame, a motor, propellers for driving the machine, means for holding the machine in a fixed position while suspended and for directly reversing its ends relatively to its direction of progress, said means comprising reversible inclined lifting planes adapted to intercept the currents of said propellers, means for moving said planes obliquely against said currents, and means for varying the inclination of said planes. 90
37. In a flying machine, the combination of a frame, transverse crank shafts mounted therein, a motor to rotate said shafts, lifting planes rotatably attached to said shafts, means for impelling a current of air against the under surfaces of said planes, and means for adjustably inclining said planes with respect to the currents of said propellers. 100
38. In a flying machine the combination of a wheel mounted frame, folding sustaining planes, adjustably attached to said frame, means for folding and unfolding said planes and means for varying their inclination, a motor disposed within the frame, air propellers operated by said motor, inclined lifting planes adapted to be operated by said motor, and means for varying the inclination and direction of movement of said lifting planes. 105
39. In a flying machine, a frame, a motor a plurality of planes, means for pivotally adjusting said planes, propellers operated by said motor and adapted to lead a current of air along said planes, means for deflecting said current by the inclination of said planes with respect to said current and means adapted to deflect said current by the movement of said planes relative to said frame against said current. 115
40. In a flying machine, a frame, propellers, adjustably inclined planes adapted to intercept the currents of said propellers and convert their force into other forms of energy, and means comprising a motor and intermediate gearing adapted to increase 120
- 125
- 130

said energy by moving said planes diagonally against said current relative to said frame.

41. In a flying machine, the combination of a frame, a motor therein, adjustable lifting planes reciprocated by said motor in a fore and aft direction with respect to said frame, means comprising air propellers operated by said motor, adapted to create an upward pressure against said planes during their forward movement and to counteract the downward pressure against said planes caused by the atmosphere during their rearward movement by propelling a current of air against the under surface of said planes.

42. In a flying machine, a frame, a motor, a plurality of planes, means for tilting said planes, means for moving said planes diagonally across said frame, propellers adapted to impel a current of air against said planes in such a way that the relative velocity of the planes and the current results from the forward movement of the planes with respect to the frame plus the rearward movement of the current, and the pressure against said planes is caused by the combined velocities of the planes and the current moving diagonally against each other.

43. In a flying machine having a wheel-mounted frame, a motor, inclined levitating planes and air propellers disposed within said frame, means for creating lift by moving said planes in a forward direction with respect to said frame, and means for increasing said lift by impelling a current of air against the under surfaces of said planes in a rearward direction.

44. In a flying machine, a frame, reversible propellers, a plurality of planes, means for tilting said planes, and means for imparting a movement to said planes diagonally forward with respect to said frame against the currents of said propellers.

45. In a flying machine, a frame, a plurality of propellers, a plurality of planes, means for tilting said planes, means for moving said planes diagonally against the propeller currents in such a way that the pressure against said planes is the result of the downward and forward movement of said planes with respect to the frame, plus the rearward movement of the currents created by the propellers.

46. In a flying machine, a frame, propelling and levitating means comprising reversible air propellers and planes, the latter adapted to intercept the currents of said propellers, means for inclining said planes with respect to said currents, and means comprising a motor and intermediate gearing adapted to move said planes relatively to said frame in a direction obliquely against said currents.

47. In a flying machine, air propellers adapted to impel a current against adjust-

ably inclined planes, means for varying the inclination of said planes, and means for increasing the force of said current, comprising a motor and power transmitting mechanism adapted to move said planes bodily within said frame in a direction against said current.

48. In a flying machine, a frame, levitating planes mounted therein, means for moving said planes in a downward and forward direction with respect to said frame, means for increasing the levitating power of said planes, said means comprising air propellers adapted to impel a rearwardly directed current of air against the under surfaces of said planes, and a motor for operating said air propellers.

49. In a flying machine, a frame, a plurality of reversible air propellers adapted to create a rearwardly directed current of air, a plurality of adjustably inclined planes and means for moving said planes with respect to said frame in a forward direction against said current, in such a way, that the pressure against said planes results from the combined velocity of movement of the planes and the current relative to each other.

50. In a flying machine, a frame, a motor, reversible air propellers operated thereby, a plurality of planes, means for varying the inclination of said planes with respect to the currents of said propellers, and means for moving said planes with respect to said frame in a direction diagonally across the said currents.

51. In a flying machine, propelling and levitating means comprising adjustably inclined reciprocating planes and air propellers adapted to impel a current of air against the under sides of said planes, a motor, a crankshaft, speed-varying mechanism attached thereto and adapted to operatively connect said propellers and planes, and means comprising relief-cocks attached to the cylinders of said motor and adapted to eliminate the compression in said cylinders in such a way that the propellers and planes are free to operate by other means.

52. In a flying machine, a frame, reversible propellers, adjustably inclined levitating planes, means for moving said planes in a forward direction with respect to said frame against the rearwardly directed currents of said propellers, partly inclosed paddle-wheels operatively connected with said propellers, a motor, a crankshaft adapted to connect said planes with said propellers and paddle-wheels, relief valves attached to the cylinders of said motor adapted to prevent compression within said cylinders and permit said propellers, planes and paddle-wheels to be operated by other means.

53. In a flying machine having a frame, the combination of reversible air propellers, propelling and levitating means, comprising

- paddle wheels and adjustably inclined planes, means for moving said planes diagonally forward with respect to said frame and across the rearwardly directed currents generated by the propellers and a power-transmitting mechanism to operate said paddle wheels and planes when the propellers are rotated.
54. In a flying machine, a frame mounted on propelling and guiding wheels, a motor disposed within said frame, propellers adapted to be rotated by air currents, a plurality of inclined levitating planes mounted in said frame, adjustable means for guiding said planes in a forward and downward direction, and means comprising variable speed and power transmitting mechanism for operatively connecting said inclined planes and said propelling wheels with said propellers.
55. In a flying machine, a plurality of reversible propellers adapted to be rotated by air currents, propelling wheels intergeared with said propellers, casings partly inclosing said wheels, paddles attached to said wheels, a plurality of reciprocating levitating planes arranged in oppositely moving groups, a motor, a crankshaft adapted to operatively connect said planes with said propellers and wheels, relief valves attached to said motor, and means for simultaneously opening said valves to cut out said motor.
56. In a flying machine, the combination of propellers adapted to be rotated by air currents, reciprocating levitating planes, joined in oscillating groups, propelling wheels, and means comprising power transmitting and variable speed mechanism,
- whereby said planes and propelling wheels 40 may be operated upon the rotation of said propellers.
57. In a flying machine, the combination of propelling and levitating means, comprising propelling wheels and reciprocating inclined planes arranged in compensating oppositely oscillating groups, reversible propellers, adapted to be operated by air currents, and means for transmitting to said wheels and planes the power generated in 55 said propellers.
58. In a flying machine, means for converting the relative movement of the machine with respect to the air into levitating and propelling force, said means comprising the combination of reversible propellers adapted to be rotated by air currents, co-operating groups of levitating planes, oscillating in opposite directions, and propelling wheels operatively connected with and 60 adapted to be operated upon the rotation of said propellers.
59. A flying machine, having reversible air propellers adapted to be rotated by air currents, reciprocating levitating planes arranged in pairs, and attached to oppositely disposed cranks, propelling wheels and means comprising variable speed transmitting mechanism for operating said planes and wheels by the rotation of said propellers.

Signed by me at New York city, (Manhattan,) N. Y., this 8th day of October, 1909.

HERMANN REICHE.
